UNITED STATES PATENT OFFICE.

ISAAC NICODEMUS, OF HENRY COUNTY, SAMUEL BURKIN, OF RUSH COUNTY,
AND HAVILAH ADAMSON, OF FULTON COUNTY, INDIANA.

IMPROVEMENT IN VEHICLE-SPRINGS.

Specification forming part of Letters Patent No. **154,803**, dated September 8, 1874; application filed
July 22, 1874.

To all whom it may concern:

Be it known that we, ISAAC NICODEMUS, of Henry county, SAMUEL BURKIN, of Rush county, and HAVILAH ADAMSON, of Fulton county and State of Indiana, have invented certain new and useful Improvements in Spring-Equalizers; and we do hereby declare the following to be a full, clear, and exact description of the invention, such as will enable others skilled in the art to which it pertains to make and use it, reference being had to the accompanying drawings, which form part of this specification.

Our invention relates to an improvement in spring-equalizers, and is intended as an improvement upon the patent granted to David Barb and Elijah Neff, April 28, 1874, No. 150,124; and it consists in the arrangement and combination of devices, which will be more fully described hereafter.

The accompanying drawing represents our invention.

a represents the axle, to which the single spring *c* is secured in the usual manner. To the top of this spring is secured a rod, bar, or plate, *d*, which may be of any desired length, and upon which the bed or body of the vehicle rests. To each end of this bar is secured a vertical rod, *g*, which has its opposite end pivoted to the horizontal curved levers *i*, the inner end of each of these levers being slotted and connected together by means of a suitable bolt or other fastening, so that when one

is moved the motion will be instantly communicated to the other. Whenever there is the slightest inequality of pressure or weight upon the bed, the sagging or tilting upon that side, causing an unequal strain upon the spring, is at once transmitted through the vertical and horizontal rod and lever upon that side to the rod and lever upon the other side, whereby the pressure is at once equalized upon the spring.

We are aware that a device similar to this has been applied to wagons where four springs are used, and this we disclaim.

By the arrangement of devices here shown we dispense with several parts which are absolutely necessary there, and are enabled to apply these devices to vehicles in which only two springs are used.

Having thus described our invention, we claim—

The combination of the single elliptical spring *c*, bar *d*, vertical rods *g*, and horizontal levers *i*, having slotted ends, substantially as shown and described.

In testimony that we claim the foregoing we have hereunto set our hands this 7th day of July, 1874.

ISAAC NICODEMUS.
SAMUEL BURKIN.
HAVILAH ADAMSON.
